ATTORNEY

UNITED STATES PATENT OFFICE.

LUKE ESKES, OF COAL HARBOR, NORTH DAKOTA.

SICKLE BAR.

Application filed July 16, 1920, Serial No. 396,657. Renewed February 6, 1922. Serial No. 534,594.

To all whom it may concern:

Be it known that I, LUKE ESKES, a citizen of the United States, residing at Coal Harbor, in the county of McLean and State of North Dakota, have invented new and useful Improvements in Sickle Bars, of which the following is a specification.

My present invention pertains to sickle bars for embodiment in the cutting mechanism of harvesters, binders and the like.

Practical experience extending through a period of many years has demonstrated that as a rule sickle bars break at the last rivet hole of the malleable iron sickle bar head or adjacent to the said rivet hole. Experience has also demonstrated that such breaks are caused by the lifting strain imposed on the bar incident to operation of the machine, from vibrations as well from heavy grass or strain presented to the cutting mechanism. The vibrations bring about crystallization of the steel and cause the rivets to wear and work loose, and the break follows.

Therefore the object of my invention is the provision of a trussed sickle bar which by reason of its characteristics is not liable to break in practice.

To the attainment of the foregoing the invention consists in the improvement as hereininafter described and definitely claimed.

In the accompanying drawings, hereby made a part hereof:—

Figure 1 is a front elevation of a sickle bar embodying my invention.

Figure 2 is a longitudinal central section of a portion of the sickle bar on an enlarged scale drawn on the section line 2—2 of Figure 3.

Fig. 3 is a plan view of the bar.

Similar numerals of reference designate

corresponding parts in all of the views of the drawings.

My novel sickle bar is formed in one piece of malleable iron or other metal compatible with its purpose, and is peculiar in that it is provided with an intermediate portion of increased thickness, as indicated by 1. One side 2 of the bar is straight, and the other side thereof is bellied as shown to afford the comparatively thick portion. It will also be observed that at the bellied portion side of the bar, the bar is tapered as indicated by 3 toward the end portions 3^a of the bar which end portions 3^a are straight at their sides opposite to the flat side 2. At intervals in its length the bar is provided with rivet holes 4 for the connection of knives (not shown) as well as the bar head, (also not shown).

It is to be understood that the comparatively thick portion 1 of the bar is to be of such relative size as not to interfere with free play of the bar.

Having described my invention, what I claim and desire to secure by Letters-Patent, is:—

As a new article of manufacture, a one-piece sickle bar flat and straight at one side and having at its opposite side an intermediate bellied portion, the ends of which are connected by inclinations with the end portions of the bar; the said end portions being of one degree of thickness and the intermediate bellied portion of a greater degree of thickness, and the bar being provided at intervals in the comparatively thick portion and the end portions with vertically disposed apertures.

In testimony whereof I affix my signature.

LUKE ESKES.
